UNITED STATES PATENT OFFICE

2,270,346

PORTABLE TRANSFER AND HOIST

Jacques Roussou, Chicago, Ill.

Application April 22, 1940, Serial No. 330,844

14 Claims. (Cl. 214—38)

This invention relates to laundry appliances or equipment and more especially to a novel portable transfer and hoist for receiving damp wash laundry from an agitator in which the washed laundry in a relatively tightly compact and somewhat tangled condition as a batch or mass has been reduced to a damp and relatively loose and fluffed or softened untangled condition ready for ironing or feeding into an ironing machine or mangle and for convenient handling by the operators and delivery into the ironing machine with less manual labor and with efficiency and dispatch.

Another object of the invention is to provide a novel portable wheeled frame having a container, vat or tank adapted to be positioned in convenient relation to an agitating machine as well as to an ironing machine, to be loaded from the agitating machine and having means operable in conjunction with a hoist to elevate the damp clothes when the device is placed in convenient position for feeding the clothes or laundry into the ironing machine by the operators and to elevate the laundry when the upper most portion thereof has been fed into the ironing machine so as to obviate the necessity of reaching into the bottom of the wheeled frame so that the feeding operation can be carried on efficiently and with less manual labor.

Another object of the invention is to provide for the connection and disconnection of the elevator frame and platform or basket within the wheeled frame so that when all of the laundry therein has been fed into the ironing machine and the elevator lowered to the bottom of the wheeled frame, the latter may be readily moved about and again placed in convenient relation to receive the damp laundry from the agitating machine.

Another object of the invention is to provide a hoist for the elevator platform which is self-compensating to adjust itself to the position of the container, vat or tank when disposed in feeding position with respect to the ironing machine.

Further objects and advantages will appear and be brought out more fully in the following specification, reference being had to the accompanying drawings, in which:

Fig. 1 is a front elevation of a portable transfer and hoist in accordance with the invention and positioned adjacent to an ironing machine;

Fig. 2 is a central vertical section taken on the line 2—2 of Fig. 1;

Fig. 3 is a fragmentary vertical section taken on the line 3—3 of Fig. 1;

Fig. 4 is a vertical section taken on the line 4—4 of Fig. 1;

Fig. 5 is a detailed face view or elevation of a connection between the hoist and the elevator frame or basket;

Fig. 6 is a plan view of the structure shown in Fig. 5;

Fig. 7 is a detailed face view or elevation of a connecting plate;

Fig. 8 is a plan view of the structure shown in Fig. 7;

Fig. 9 is a transverse vertical section showing the device applied to an agitator for receiving the damp laundry therefrom;

Fig. 10 is a plan view of the elevator frame or basket removed from the vat or tank of the wheeled frame;

Fig. 11 is a top plan view of a slatted platform forming the bottom of the elevator frame or basket;

Fig. 12 is a longitudinal vertical section of the basket shown in Fig. 10 with the slatted bottom or platform shown in Fig. 11 in position therein;

Fig. 13 is a horizontal plan section of the elevator basket within the container or tank of the wheeled frame;

Fig. 14 is a side view of the hoist;

Fig. 15 is an end view of the hoist;

Fig. 16 is a section taken on the line 16—16 of Fig. 14; and

Fig. 17 is a section taken on the line 17—17 of Fig. 14 illustrating the control for the hoist.

Referring to the drawings, 20 designates a wheeled frame bearing a container, vat or tank 35 and comprising a bottom frame 21 horizontally positioned and preferably made of angle iron rendered rust proof by galvanizing, enameling or otherwise. The side angle bars 22 run longitudinally and are connected to the end angle

bars 23 by welding or otherwise. Suitable parallel transverse cross members 24 are provided in the form of angle bars or otherwise and shown below the bars 22 and 23. Two pairs of angle bars 24 disposed closely adjacent and near the ends of the frame support swiveled casters 25 with cushion rollers if desired, these casters being adapted to turn about. The frame is also reinforced by a bottom cross strip 26 which may be connected to the innermost bars 24 as by

means of diagonal braces 27 to produce a strong and rigid bottom frame and portable frame structure. The front corner posts, or upright frame members are designated at 28 and corresponding rear members at 29 and may be connected to the bottom frame members 22 and 23 and

the latter also connected to each other through the medium of gusset plates 30 welded, riveted or otherwise secured in position. A longitudinal bar or rim 31 is provided between the uprights 28 at the top of the wheeled frame and may also be of angle iron with a vertical outer flange and a horizontal inwardly extending top flange. A longitudinal bar or rim 32 is provided at the top of the inside or back of the wheeled frame between the corner posts 29 and may be of composite construction to form an inverted U-shaped member, but the top flange of the bar 32 extends outwardly as distinguished from the inwardly extending flange 31 and the other flange extends vertically at the inside for connection with the vertical members of the frame by welding or otherwise. The container, vat or tank is produced by means of a lining 33 which may also be fastened to the vertical flanges of the bars 31 and 32, and as shown at 34, may be passed over the top flange of the bar 32 to extend outwardly and downwardly in spaced relation as at 35 to form a channel member and also give increased strength and stiffness at the side and rim which is normally disposed toward the agitating machine and the ironing machine, as will be later described. The depending flange at this point is shown at 35, thus producing an inverted U-shaped guard rail with a depending flange at the outside. Vertical members 36 may connect the upper and lower portions intermediate the ends thereof with diagonal braces 37 outwardly thereof, all connected between the upper and lower bars 31 and 22 and 32 and 22, these being the bars which run horizontally and longitudinally of the wheeled frame.

An elevator frame is provided for the container, vat or tank of the wheeled frame and includes a platform or basket 38 consisting of longitudinal side bars 39 such as angle iron, connected to the end bars 40 with gusset plates 41, if desired, by welding or otherwise. Cross strips or braces 42 may be arranged transversely between the bottom flanges of the longitudinal bars 39. Upright end posts 43 are provided intermediate of the ends and may be rendered rigid by inclined or diagonal braces 44 preferably at the front. The upright end posts 43 are preferably of flat stock and the braces 44 are connected thereto near their upper ends and to the bars 40. The bar 39 will engage the bar 31 at one side of the wheeled frame having the container, vat or tank, to limit upward movement or displacement of the elevator frame or platform 38 while traveling vertically, but permitting removal thereof laterally or horizontally above the low side.

In order to provide means for detachably connecting the elevator platform, frame or basket to a hoist, the uprights 43 are provided near their upper ends and on their inner faces with buttons 45 shown of rectangular formation located horizontally and having reduced squared shank portions 46, these buttons being bolted or riveted through to the uprights 43 which are apertured for this purpose. One end of each head 45 is 65 beveled or tapered as indicated at 47.

A slatted removable bottom 48 is provided for the elevator frame or platform 38 and consists of spaced parallel transverse cleats 49 adapted to rest on the horizontal flanges of the bars 39 and 70 40 connected by closely adjacent spaced parallel strips 50 running longitudinally. This slatted bottom is adapted to be bodily placed within the elevator frame, platform or basket.

A key plate 51 having a suitable aperture near 75

one end is provided with a longitudinal slot 52 having an intermediate circular enlargement 53 produced by opposed concavities at the edges of the slot and the aperture of the plate is connected 5 to a chain or cable 54. Two of such plates and chains are provided, it being understood that these plates are designed to be detachably engaged with the buttons 45, the plates 51 being engaged with the buttons in the positions shown 10 in Figs. 5 and 7 and then the plates turned vertically at a ninety degree angle by reason of the concaved recesses 53 so that the heads of the buttons will straddle the slots 52 and prevent displacement of the plates, but may be turned horizontally for disengagement thereof assisted by 15 the beveled portions 47. The upper ends of the chains or flexible connections 54 are connected at 55 to suspension means including a suspension or truss frame 56 consisting of a horizontal bar 57 shown in the form of a pipe or tubular element having a central strut or upright 58 connected at its upper end by braces 59 to the ends of the bar 57 as through the medium of the I-bolts 55. The upright 58 above the connection of the braces 59 therewith has a hole 60 for engagement by a hook 61 swiveled at 62 to a block or weighted enlargement which forms a bumper as will be later described, and is in turn connected to a flexible connection or chain 63 operating to wind and 20 unwind or be raised and lowered by a hoist 64 which may be of any suitable type. This hoist is shown suspended by a hook 65 from a hanger 66 at the ceiling or other elevated support and has a driven sprocket 67 operated by the reversing 25 and reducing gear 68 from a motor 69. The chain, after passing over the sprocket 67 is formed into a depending loop 70, one lap of which has connection at 71 to the motor casing with an interposed spring 72 to cushion the reversing or checking movements of the drive and elevator 30 frame. A cable 73 carries the electrical energy to the motor or through a switch 74 provided for thus controlling the operation of the motor including the starting and stopping as well as 35 the reversing thereof. A pivoted cross arm 75 is mounted between the switch box and the motor as shown in Figs. 14 and 17 and is limited in its movements by a stop pin 76. An "up" pull cord 77 is connected to one end of the cross arm 75 and a similar "down" pull cord 78 is connected 40 to the other end while a pivoted fork 79 is mounted beneath the motor at the reducing and reversing gear to be engaged by the abutment or bumper 62 should the upward movement of the 45 elevator platform proceed to such position, in which instance the fork will strike the depressed portion of the cross arm 75 on either side of the pivot thereof and dispose of same in a neutral position thereby opening the switch to the motor. Brake shoes 80 are provided on the motor casing 50 to operate on the shaft thereof and are held by springs 81, but adapted to be expanded by a shoe expander 82 and connected to the pivot of the cross arm 75 of the switch so that when the switch is in a neutral position the shoes will be 55 engaged, but when the switch is operated to raise or lower the elevator platform the expander will separate the brake shoes so as not to retard the 60 operation of the motor.

The hoist is disconnected from the elevator platform and basket after the latter is lowered into the container, vat or tank of the wheeled frame in the manner shown in Fig. 9 and by disconnecting the plates 51 from the buttons 45, the 65 wheeled frame may be moved about and posi-

tioned adjacent to the agitating machine 83. This machine has a horizontal drum or cylinder 84 with a door opening 85 and has a channel rail 86 at one side adjacent the door opening and may be connected to the wheeled frame by a transfer plate 87 having a channel 88 to engage the channel 86 or other suitable bar at the side of the agitating machine and preferably so that the transfer plate will be inclined toward the low side of the wheeled frame. A channel 89 is provided at the other end of the transfer plate to engage the bar or channel 85 so that the damp wash laundry may be discharged from the agitating machine into the tank or vat 33. The transfer plate is then disconnected and the wheeled frame moved beneath the hoist 64 adjacent or against the ironing machine or mangle indicated at 90 and the plates 51 connected with the buttons 45 upon pulling the cable 78 to lower the same if not already down, or this connection may be made after some of the laundry has been removed from the top of the batch and fed into the ironing machine. As the supply is lowered the elevator frame may be raised by simply pulling on the switch cord 71 or lowered by pulling on the switch cord 78.

The ironing machine is shown provided with control or starting levers 91 and a clutch lever 92. The ironing cylinders are designated at 93 and 94 while 95 is a feed roller mounted on a shaft 96 in adjustable bearings 97 operated by screws 98 having suitable operating wheels. A sprocket 99 on the shaft 96 is engaged by a chain 100 driven in any suitable manner by a motor or other driven part of the machine. Ribbon belts 101 are trained on the feeding roller 95 and also around a small idler roller 102 and over an apron 103 which supports the upper laps of the belts. A weighted roller 104 engages the work or towels 105 as the latter are fed into the ironing machine in the manner depicted in Fig. 2 of the drawings. A ticket holder or clip 106 may be provided on the front or high side of the wheeled container on the bar 31 to hold the laundry tickets referring to the batch contained in the vat and being moved from the agitating machine and then passed into the ironing machine. By having the elevator platform or basket capable of being raised to the degree desired within the wheeled container or tank, the operator can readily grasp the clothes while remaining in convenient position for feeding the laundry into the ironing machine and in this way the work is facilitated without needless bending over, and therefore the work may be carried on with greater facility and considerable economy.

In view of the foregoing it is thought that the construction and operation of the device will be readily understood and therefore further description thereof is omitted.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. A portable transfer including a transportable frame having a container, a platform mounted therein, one side of the frame extend-

ing inwardly over the container and the other side being lower than the first side, the inwardly extending side limiting the upward movement of the platform above the low side to permit removal of the platform laterally above the low side.

2. A portable transfer including a wheeled frame and having side walls of considerable depth, an elevator frame and platform mounted therein to move up and down, one side extending inwardly at the top above said side walls and the other side being lower than the last mentioned side, the inwardly extending side limiting the upward movement of the elevator frame and platform at one side to permit horizontal removal of the elevator frame and platform over the opposite side.

3. A portable transfer including a transportable frame having a container, a reticulated platform mounted to move up and down therein, a bar at one side of the platform, said container having an inwardly extending portion above the container to limit the upward movement of the platform by engagement of the bar therewith above the top of the container to permit removal of the platform laterally thereover toward the opposite side.

4. A portable transfer including a wheeled truck with a container having side walls, an elevator platform mounted loosely therein, one side of the container extending inwardly at the top and the other side being lower than the first side and extending outwardly, the inwardly extending side limiting the upward movement of the platform above the low side to permit removal of the platform laterally above the low side.

5. A portable transfer including a transportable frame having a container, said frame having longitudinal top bars, one bar being located above the top of the container and extending inwardly and the other bar extending outwardly of the container at the top thereof below the aforesaid bar, an elevator platform mounted to move up and down in the container and means for suspending the platform for such movement and for removal horizontally over the outwardly extending bar.

6. A portable transfer including a transportable frame having a container with vertical side walls, said frame having longitudinal top bars, one bar extending inwardly, a platform adapted to move up and down in the container, said platform adapted to strike the inwardly extending bar at its upper limit above the other top bar for removal horizontally over the latter bar, means for suspending the platform for movement up and down and limiting the upward movement thereof while permitting horizontal movement thereof.

7. A portable transfer including a transportable frame, a reticulated basket mounted to move up and down in the frame, one side of the frame being higher than the other and having means at the top to limit the upward movement of the basket above the opposite side and a transfer plate having end channels adapted to engage over the low side and over the edge of the door opening of an agitating machine or the like.

8. A portable transfer including a wheeled container, a basket mounted therein and having upwardly extending suspension means, a stop over the container above the top thereof at one side for engagement by the basket when the latter is raised above the opposite side, the last men-

tioned side being freely open and unobstructed at the top to permit horizontal displacement of the basket over the latter side.

9. A portable transfer including a wheeled container, a slatted basket mounted therein, means to limit the upward movement of the basket in the container at one side but to permit horizontal lateral displacement and removal thereof from the container toward the opposite side, means for raising and lowering the basket including suspension means and means for automatically checking the raising of the basket.

10. A portable transfer including a wheeled container, a slatted basket mounted therein, means to limit the upward movement of the basket in the container at one side but to permit horizontal lateral displacement and removal thereof from the container toward the opposite side, means for raising and lowering the basket and detachably connected thereto, said raising and lowering means and basket having cooperative means to automatically stop the raising of the basket upon reaching a certain elevation.

11. A portable transfer including a wheeled container, a slatted basket mounted therein, means to limit the upward movement of the basket in the container at one side but to permit horizontal lateral displacement and removal thereof from the container toward the opposite side, means for raising and lowering the basket and detachably connected thereto, said raising and lowering means having an operating motor and means cooperative between the suspension

means and the basket to automatically shut off the motor upon the basket being raised to a certain point.

12. A portable transfer including a transportable frame having a lining, an elevator therein to move up and down, means at one side of the lining to prevent removal of the elevator therefrom at said side, said elevator being adapted for connection with a suspension means to raise and lower the elevator and the other side being freely open to permit removal of the elevator laterally thereabove when at the upward limit of its movement at the opposite side.

13. The combination with a portable transfer including a wheeled frame having a lining, an elevator platform mounted loosely therein for movement up and down, suspension means for the platform, uprights at the ends of the platform, and means for detachably securing the uprights to the suspension means, said means being engageable and displaceable by movement horizontally from its vertical or secured position.

14. A portable transfer including a transportable frame having a lining, said frame having longitudinal top bars, one bar being higher than the other, means for connecting the lower bar to an agitating machine, an elevator in the frame and means at the high side of the frame to limit the upward movement of the elevator for removal laterally over the low side.

JACQUES ROUSSO.
